COMBINED WHEEL CHOCK AND FLAG

Ralph V. Switzer, Park Ridge, Ill., assignor to The Aldon Company, Chicago, Ill., a corporation of Illinois

Filed Feb. 7, 1966, Ser. No. 952

Term of patent 14 years

(Cl. D41—1)

FIG. 1 is a front perspective view of a combined wheel chock and flag showing my new design;

FIG. 2 is a front elevational view thereof;

FIG. 3 is an end view thereof as viewed from the right of FIG. 2;

FIG. 4 is a top plan view thereof.

The broken lines are for illustrative purposes only.

I claim:

The ornamental design for a combined wheel chock and flag, as shown and described.
